(57) **CLAIM**

The ornamental design for a case for an electronic device, as shown and described.

DESCRIPTION

FIG. 1 is an upper side view of the case in accordance with a first embodiment of the invention.

FIG. 2 is a rear view of the case in accordance with a first embodiment of the invention.

FIG. 3 is a right side view of the case in accordance with a first embodiment of the invention.

FIG. 4 is a left side view of the case in accordance with a first embodiment of the invention.

FIG. 5 is a lower side view of the case in accordance with a first embodiment of the invention.

FIG. 6 is a front view of the case in accordance with a first embodiment of the invention.

FIG. 7 is a front-right perspective view of the case in accordance with a first embodiment of the invention.

FIG. 8 is a front-view cutaway of the case in accordance with a first embodiment of the invention.

FIG. 9 is an upper side view of the case in accordance with a second embodiment of the invention.

FIG. 10 is a rear view of the case in accordance with a second embodiment of the invention.

FIG. 11 is a right side view of the case in accordance with a second embodiment of the invention.

FIG. 12 is a left side view of the case in accordance with a second embodiment of the invention.

FIG. 13 is a lower side view of the case in accordance with a second embodiment of the invention.

FIG. 14 is a front view of the case in accordance with a second embodiment of the invention.

FIG. 15 is a front-right perspective view of the case in accordance with a second embodiment of the invention; and,

FIG. 16 is a front-view cutaway of the case in accordance with a second embodiment of the invention.

(Continued)

The broken lines shown in the figures are for the purpose of illustrating structure that forms no part of the claimed design.

1 Claim, 10 Drawing Sheets
